FIG-9FIG-10FIG-11FIG-12FIG-13## ELASTOMERIC RAILWAY CAR SIDE BEARING

This is a continuation-in-part application of my co-pending application Ser. No. 283,044 filed Aug. 23, 1972, now abandoned.

BACKGROUND OF THE INVENTION

This invention relates to the art of dynamic stabilization of all types of railway cars and particularly in transit on standard roadbeds by the absorption of energy of shock and the dampening and limitation of dynamic motion of the body of the car in the vertical, lateral and horizontal or swaying directions.

Side bearings embodying rollers movably mounted in a housing supported on a truck bolster which are contacted by the car body are old. Also, some preloaded side bearings are known to utilize spring-loaded cam systems. Insofar as solving the problem of dynamic rocking motion resulting in derailment of railroad cars, and hunting, snubber members have been used in conjunction with the springs between the truck bolster and the side frame of the car. None of the foregoing have been found to provide an inexpensive structure which will reduce the dynamic condition which causes the car bodies to sway from side-to-side under self-excited vibration and create a problem which is known in the railroad industry as resonant "rock and roll." More specifically, this condition has been encountered with high covered hopper cars and some high-side gondolas capable of carrying between 100 and 125 tons of material. These cars are normally approximately the same length as the standard rail and with the staggered joints between the rails and a forced resonant vibration condition, can be set up at some of the lower speeds of travel.

As now understood, this swinging of the car body from one side to the other contacts the side bearing which is located between the car body and the truck bolster. The forces are transmitted through the bolster and into the spring group and the side frame of the truck. From there, the force goes to the car journals and onto the axles on the outboard side of the wheels of the truck. This causes the wheels and the rail on that particular side to form a fulcrum point, lifting the wheel from the track on the opposite side. Most of the time the wheels on the far side return and make contact with the rail. In newer cars with larger loads and greater excitation forces, the wheels, on returning to the level, miss the rail, causing derailments. A second condition which is causing derailments occurs when the dynamic rocking of the car becomes so violent that the forces transmitted down through the truck bolsters and frame into the wheels are great enough to actually turn the rail over on the tie.

Swinging of the car body from side-to-side also can result in lateral directional hunting of the truck which, if undampened and unlimited by constant contact with a side bearing, leads to excessive wheel flange wear and centerplate wear.

Many designs of freight car side bearings have been tried in the last fifty years. Most of these designs failed because they were too complicated and not made of resilient material capable of absorbing high dynamic forces of both long and short duration. Other designs failed though made of resilient material because they were not adequately supported on the top of the truck bolster side bearing pad.

There is thus a need in the railroad industry for a low cost, preloadable, constant contact side bearing which retains its original resilience throughout its life and which stabilizes the dynamic motion of a freight car in transit at all reasonable operating speeds and rated car loadings with non-linear load response action while limiting maximum travel with steel controlled stops. Reduction of rocking of the car, lift of the wheels off the rail and lateral hunting of the trucks by means of position action shock control of the freight car motion through the use of such side bearings will reduce excessive wear of rail, wheel and equipment during life, and lead to trouble-free maintenance during operation and improve customer service relations from reduced damage to lading for sales.

It is thus an object of this invention to provide for energy-absorbing, elastic, constant contact truck side bearings satisfying the above need.

SUMMARY OF THE INVENTION

The inventive concept involved in this improved side bearing for railroad cars comprises a hard elastomeric side bearing, preferably polyurethane of a hardness of at least 60 to 90 Shore D scale, an upright body member being positioned in a restraining housing, for maximizing of resilient energy absorption. A structural steel housing may support the resilient absorber bearing in the four lateral dimensions, as well as from the bottom, and permit the absorption and stabilization of dynamic forces of car motion by compressive travel thereof which is resisted by non-linear load response from above, while at the same time limiting compressive travel with steel controlled travel stops and sidewise shearing movement from lateral forces applied thereto. The housing itself functions as a mechanical stop for limiting both the vertical compressive travel between the body side bearing wearplate and the truck bolster side bearing pad, and the lateral shear deformation of the resilient absorber mounted therebetween.

With large capacity cars, with higher centers of gravity, loads at the side bearing are considerably increased in magnitude. Further, due to the design and geometry of freight cars, the loads or reactions at the side bearing are not hammer blows, but rather have a definite dwell period. During this period of dwell, the constant contact side bearing is required to take as much, or more, of the car body weight as the center plate.

Not only must the truck side bearing take large vertical forces, but it is also called upon to take sizable lateral forces from the car body. The structural steel housing has the capacity to withstand these high lateral forces and to limit the lateral shear formation of the resilient absorber contained therein and to stabilize lateral car motion resulting therefrom.

Another object of this invention is to provide elastic truck side bearings which provide toughness and resistance to abrasion and having the ability to absorb energy and to dampen the vertical, lateral, longitudinal and swaying shock forces having their origin in high speed and heavy load travel thereby preventing wear and tear on the rolling stock and the rails and roadbeds of the railroad.

65 BRIEF DESCRIPTION OF THE DRAWINGS

FIG. 1 is a perspective view of the resilient side bearing of this invention;

FIG. 2 is a perspective view of a truck bolster showing the resilient side bearing mounted thereon;

FIG. 3 is a fragmented top view of the truck bolster showing the resilient side bearing mounted thereon;

FIG. 4 is a fragmented side view of the car body and truck bolsters assembled on the center plate with the resilient side bearing mounted therebetween compressed from free height;

FIG. 5 is a perspective view of the tapered end upright member of this invention;

FIG. 6 is a fragmented cross-sectional view on the line 6—6 of FIG. 1 of a resilient side bearing having a top of isosceles trapezoidal shaped cross-section mounted on an upright body member assembled within a structural steel housing;

FIG. 7 is a fragmented cross-sectional view of a modified form of resilient side bearing having a rectangular-shaped cross-section assembled within a structural steel housing;

FIG. 8 is a perspective view of the rectangular upright member of this invention;

FIG. 9 is a perspective view of a modified form of the invention;

FIG. 10 is a perspective view of the device shown in FIG. 9;

FIG. 11 is a perspective view of another modified form of the invention;

FIG. 12 is a perspective view of the device of FIG. 11; and

FIG. 13 is a cross-sectional view taken on the line 13—13 of FIG. 12.

DETAILED DESCRIPTION OF THE DRAWINGS

Side bearings 10 that are the subject invention, as shown in FIG. 1, are horizontally mounted on the top of a truck bolster 12 spaced equi-distant to each side of center plate 14 thereon which is part of railway car bogie 16, as shown in FIG. 2. A truck bolster side bearing pad 18 which is structurally integral with the top of truck bolster 12 and spaced equi-distant by an amount equal to the spacing of side bearings 10 to each side of center plate 14 provides the flat surface on which the base 26 of the side bearing 10 is bolted to the truck bolster 12, as shown in FIGS. 3 and 4. A body bolster 20 is mounted atop center plate 14, as shown in FIG. 4. A body side bearing wear plate 22 is horizontally mounted on the under side of the body bolster 20 and also spaced equi-distant by an amount equal to the spacing of side bearings 10 to each side of center plate 14 thereon, as shown in FIG. 4. An upright body member 34 which is part of and mounted within the side bearing 10 bears on plate 22. The side bearing 10 is preferably of a free height of 4 $\frac{1}{4}$ to 5 $\frac{1}{4}$ inches. The nominal vertical distance between the bottom surface of body side bearing wear plate 22 and the top surface of the truck bolster side bearing pad 18 is approximately 5 inches so that when installed, the nominal vertical compression of the side bearing 10 is about three-fourths inches.

The side bearing 10 includes a hollow, generally rectangularly shaped steel housing 24 having a rectangularly-shaped base 26, as shown in FIG. 1. Side walls 28 and 28' extend in perpendicular relation to and along each lateral edge of the base 26 and the distance between the inner faces is about 3-5/16 inches. Side walls 28 and 28' turn partially around and are shaped to become end walls 29 and 29' in encompassing relation to

the edge of each end of the base 26 to provide a hollow supporting structure within having access openings 27 and 27' at opposite ends thereof. The inside length of the housing 24 usually is of two lengths, namely about 9 inches and 12 inches. Bolt holes 30 and 30' extend through the base 26, adjacent to the opposite ends thereof, as shown in broken lines in FIGS. 1 and 3 and in cross-section in FIGS. 6 and 7, and provide for the attachment of the housing 24 to the truck bolster 12. Flanges 32 and 32' having top surfaces which are in parallel relation to and spaced above the mounting bottom surface of the base 26 are equally spaced a given distance up the side walls 28 and 28', respectively, and provide for a mechanical stop to vertical compression of the side bearing 10, under extreme conditions, such as illustrated in FIG. 4.

In one version of the side bearing 10, as shown in FIGS. 1, 5 and 6, an upright body member 34, constructed preferably of a hard elastomeric material such as polyurethane having a hardness of at least 60-90 Shore D scale, having a rectangular bottom section 36 and a top section 38 which, though rectangular in plan form, is shaped as an isosceles trapezoidal cross-section tapering upwards at both ends thereof when viewed from the side. The top section 38 of the upright member 34 mounts integrally onto the bottom section 36 and the top of the top section 38 extends above and out front between the top surfaces of flanges 32 and 32' of the steel housing 24, as shown in FIG. 1. Spaced side faces 42 and 42' establish the lateral width of the upright body 34 as uniform in dimension so that the upright body 34 fits snugly within the spaced distance between the inside dimension between the side walls 28 and 28' of the steel housing 24. This provides lateral support to the upright body 34 for resisting shear deformation thereof from lateral car forces applied thereto. The length of the upright body 34 has a dimension that fits loosely within the spaced distance of the inside dimension between the shaped turned end-walls 29 and 29' on opposite ends of the steel housing 24. Champs 37 at the four corners of the rectangular bottom section 36 permit the easy assembly of the bottom section 36 of the upright member 34 within the spaced distance between turned end-walls 29 and 29' on opposite ends of steel housing 24. Vertically spaced and downwardly extending threaded studs 44 (only one being shown) are molded in and adjacent to the opposite ends of upright body member 34 and secure the upright body member 34 to the base 26 within the steel housing 24, as shown in FIGS. 1, 3, 4 and 6. The same studs 44 are spaced to extend through pre-existing spaced bolt holes 30 and 30', respectively, as shown in FIG. 3, located in the truck bolster, to attach the side bearing 10 to the pad 18 on the truck bolster.

Another version is the side bearing 10', as shown in FIG. 8, which comprises a rectangularly shaped upright body member 34' having opposed ends 50, side faces 48 and 48', top 47 and bottom 51, preferably constructed of a like hard elastomeric material such as polyurethane of at least 60 to 90 Shore D scale hardness which is of overall rectangular section 46. The bearing 10' is placed within the hollow of rectangularly shaped steel housing 24. The lateral width between the spaced side faces 48 and 48' of the upright body 34' fits snugly within the spaced distance between the inside dimension between the side walls 28 and 28' of the steel housing 24. This provides lateral support for the

upright body 34 for resisting shear deformation thereof from lateral car forces applied thereto. The length of the upright body 34' has a dimension that fits loosely within the spaced distance of the inside dimension between the shaped turned end-walls 29 and 29' on the opposite ends of the steel housing 24. Molded-in threaded studs 49, as shown in FIGS. 7 and 8, are centrally disposed in and horizontally extend outwardly from each of the opposed ends 50 of the upright body 34'. Crossplates 52 extend laterally across the width of steel housing 24 over the openings 27 and 27' in the opposite ends thereof, as shown in FIG. 7. Only one crossplate is illustrated but the opposed one is identical to the one shown in FIG. 7. Bores 54 are centrally disposed in the crossplates 52. Studs 49 extend through the bores 54 of the crossplates 52. Nuts 56, when tightened against crossplates 52, bolt the studs 49 to the crossplates 52 and to the steel housing 24 therebetween and secure the upright body member 34' therein. The usual bolts 58 extend through the spaced bolt holes 30 and 30' and attach the side bearing 10' to the truck bolster.

The elastomeric bearings in both embodiments are thus anchored securely with the housing 24.

In the embodiment shown in FIGS. 9-13, it is desired to merely place a rectangular piece of polyurethane 60 of from 50 to 90 on the Shore D scale in the interior of the housing with the length and width being substantially the same as the inner length and width of the housing 10, with the height thereof being the same as 30 in the other embodiments.

In FIGS. 9 and 10, the length of the polyurethane is approximately 8-9/16 inches having cutouts 61 in the bottom surface and extending inwardly a sufficient amount to accommodate a portion of the head of the 35 tiedown bolt 58, as shown in FIG. 7.

In FIGS. 11 through 13, the block 62 of polyurethane being longer to accommodate the larger size housing is provided with a pair of bores 63 and 64 to fit over the heads of the usual tiedown bolts which are spaced on 40 8½ inch centers to accommodate the threaded apertures in the truck bolster 12. These dimensions are standard in railway cars.

The interior of the polyurethane may be partially hollowed out and filled with a less expensive material such as a block of polyethylene, as shown at 65.

I claim:

1. A side bearing for mounting on a truck bolster of

a railway car bogie comprising:

- a. a hollow structural housing having an open top, side, bottom and end walls, said end walls having straight vertical walls extending upwardly from said base and the upper ends of said walls arcuately tapered inwardly, and
- b. an upright body member of hard elastomeric material having a top extending upwardly and outwardly of the housing and the major portion of the body member snugly fitting therein, said body member having a bottom wall and end walls extending upwardly in a vertical direction from the bottom wall and then tapered inwardly towards the top.

2. The device according to claim 1 wherein a bolting means extends downwardly from said body member with the upper end of said means embedded in said body, said bolt means securing the housing and upright body member to the truck bolster.

3. A side bearing as set forth in claim 1 wherein the upright body member comprises:

- a. a horizontally flat bottom surface,
- b. vertical spaced side faces extending upward from said base,
- c. spaced end faces tapering upward from said base, and
- d. a bolting means including a head and a shank extending downwardly from the bottom of said body member for securing the upright member to the base member of the housing, said head and a portion of said shank embedded in said body member.

4. A side bearing as set forth in claim 3 wherein the upright member comprises:

- a. a horizontally flat bottom surface,
- b. vertical spaced side faces and end faces extending upwardly from said base, and
- c. a bolting means partially embedded in and extending outwardly from each of opposed end faces for securing the upright member to the housing.

5. A side bearing as set forth in claim 4 wherein the bolting means comprises:

- a. threaded studs extending outwardly from the opposed end faces of the upright member,
- b. bored crossplates extending laterally across the access openings at the opposed ends of the steel housing mounted on each of the studs, and
- c. threaded nuts securing said bored crossplates on said threaded studs.
